4 Claims. (Cl. 197—84)

This invention relates to typewriters, more particularly to a mechanism for the stepwise spacing operation of the paper carriage of typewriters, whereby the size of the steps is variable.

5 An object of the present invention resides in the provision of a mechanism for the stepwise operation of the paper carriage, whereby the size of the steps is variable as is particularly required in typewriters for oriental languages which have 10 characters of different widths.

In the known typewriters of this type it is not possible to change the steps of the paper carriage without fundamentally changing the machine. For the slightest modification of the once fixed 15 keyboard extensive changes must be made which are expensive because many parts of the machine must be remade. This is of particular disadvantage when trying to adapt a conventional model of typewriter for all oriental languages because 20 the great variety of these languages and of sets of characters requires various modifications of the keyboard. Also the user of a typewriter often desires to change certain type characters so that the machine must be provided with different key 25 arrangements.

It is an object of this invention to avoid these disadvantages and to provide an improved typewriter which can be easily made to fit for any idiom or keyboard of oriental languages.

30 It is another object of this invention to provide an improved typewriter in which the different spacing movements of the paper carriage can be readily effected.

Further and other objects of the present invention will be hereinafter set forth in the accompanying specification and claims and shown in the drawings which, by way of illustration, show what I now consider to be a preferred embodiment of my invention.

35 In the drawings which illustrate an embodiment of my invention by way of example, only such parts of the typewriter are shown as are essential for disclosing my invention. Other known parts of typewriters which are not essential 40 for illustrating my invention have been omitted in order to simplify the disclosure.

In the drawings:

Fig. 1 is a top view of the keyboard and key levers.

45 Figs. 2, 3, 4 and 5 are side views of four differently acting key levers and the coacting abutment and bails.

Fig. 6 is a part cross sectional view through the machine with the paper carriage in the lower case shift position.

Figs. 7, 8 and 9 diagrammatically show the cooperation of the key levers with the different abutment and transmission members when operating individual groups of keys and when the paper carriage is in the lower case shift position. 5

Fig. 10 is a part cross sectional view through the machine with the paper carriage in the upper case shift position.

Figs. 11 and 12 are individual illustrations corresponding to Figs. 7, 8 and 9 but showing the 10 coaction of the individual parts when the paper carriage is in its upper case shift position.

Fig. 13 is a part cross sectional rear view of the escapement mechanism and transmission members with the machine in rest position. 15

Fig. 14 is a rear view of the escapement mechanism showing the movable escapement pawl swung in multi-step position.

Fig. 15 is a partial section through the machine with a position of the parts corresponding to 20 Fig. 9, showing the type lever drive in type-printing position and the operation of the type levers on the carriage spacing mechanism, and the case shift mechanism.

In all figures like numerals indicate like parts. 25

As apparent from Figs. 6 and 10 of the drawings, a case shift frame 2 is movably connected to the machine frame 1 and guided by means of a slot 3 which engages pins 4 which are fixed to the typewriter frame 1. This case shift frame 30 can be set at one or more elevations as compared with the base position by means of case shift keys 70 indicated in Fig. 1 and not particularly shown because they are well known in the art of making typewriters. The shift frame 2 is provided with guides 5 for the longitudinal movement of the carriage 6. The carriage 6 which carries the writing cylinder or platen 7 is provided with a rack 8, which cooperates with the gear 9 connected to an escapement wheel 10, and 40 is stepwise moved by the action of the carriage pulling spring not shown, the steps corresponding to the width of the characters. 35

The carriage spacing mechanism consists substantially of an escapement pawl carrying body 45 11 which can rock about an axis 51 in the case shift frame 2 and which carries a fixed pawl 12 and a movable escapement pawl 14. These escapement pawls cooperate successively during the rocking of the body 11 about its axis 51, with 50 the teeth of the escapement wheel 10. When the paper carriage is stationary, the movable pawl 14 engages the escapement wheel 10 which is urged by the usual carriage pull spring in anti-clockwise direction, Fig. 13, but is prevented from 55

such movement by the pawl 14 since the arm 59 of this pawl bears against a fixed stop 60 on the body 11. Each spacing step of the paper carriage is effected by a rocking to and fro of the body 11 about its axis 57. This rocking movement of the body 11 about the axis 57 always takes place in the same manner and has no influence on the spacing distance of the carriage. The spacing step is effected in the following manner: When the body 11 rocks about its axis 57 in clockwise direction, Figs. 6 and 10, the fixed pawl 12 first engages the escapement wheel 10 and holds the same, whereupon further rocking of the body 11 in clockwise direction brings the movable pawl 14 out of engagement with the escapement wheel. After the movable pawl 14 has come out of engagement with the wheel 10, it is rocked by the action of the spring 13, Figs. 13 and 14, about its pivot 58 in the body 11, in anti-clockwise direction. This rocking movement of the movable pawl 14 about its pivot 58 determines the length of the spacing step, and it is dependent on the setting position of the abutment 16 against which the pawl 14 strikes under the action of its spring 13. The pawl body 11, therefore, immediately after the end of its clockwise movement, Figs. 6 and 10, in which the movable pawl 14 came out of engagement with the escapement wheel, returns to the position shown in Figs. 6 and 10 in which the fixed pawl 12 is again out of engagement with the escapement wheel 10, and the movable pawl 14 is in engagement with said wheel. Since, however, meanwhile the movable pawl has been rocked about its pivot 58 to the extent of a single or a plurality of teeth divisions according to the position of the abutment 16, the movable pawl 14 engages a different tooth of the escapement wheel 10, after the fixed pawl has again released the wheel 10, is rocked into its original position under the action of the escapement wheel which is under the tension of the carriage pull spring, and the spring 13 is tensioned, this position being shown in Fig. 13 in full lines and the arm 59 then lying against the stop 60. The movable escapement pawl 14 thus permits a rotation of the escapement wheel 10 corresponding to the magnitude of its previous left-hand shift about its pivot 58, Figs. 13 and 14. The essential thing for obtaining a spacing step movement of the paper carriage is thus the known to-and-fro rocking escapement body 11 and the also known escapement pawls 12 and 14. To obtain a spacing action, the body 11 must rock to and fro once about its axis 57.

The individual end position of the pawl 14, i. e., the choice of the first, second or one of the consecutive gaps according to the desired size of the steps of the movement of the paper carriage, is determined by the adjustable abutment 16 against which the pawl 14 abuts under the action of spring 13. Abutment 16 is held by means of spring 47 in a position which corresponds to the shortest step of the paper carriage 6, i. e., to the smallest swing of the pawl 14; spring 47 is built considerably stronger than the spring 13 which acts on the movable pawl 14.

In the embodiment of my invention herein described, two sizes of steps of the paper carriage movement are shown, namely, a single and a double step, and the case shift is effected by raising the whole paper carriage, but the invention is illustrated as applied to such a machine merely by way of example.

All key levers 25, viz., 25a, 25b, 25c and 25d

have support arms 27 by means of which they are hung on a common shaft 26 extending across all key levers. The levers are swung around this shaft when the corresponding keys 28 are depressed against the action of the draw springs 51 which are connected to the rear ends 29 of the key levers 25. All this is obvious from Figs. 1 to 5, inclusive.

Fig. 1 illustrates the arrangement of key levers 25 and a conventional keyboard. In addition to keys 28 for the individual characters, the back space 71, the two case shift keys 70 and the case shift lock 72 are shown. The machine is further provided with one or several dead keys 28e which do not actuate the control mechanism.

On actuating the type key 28d the key lever 25d is rocked about the shaft 26. Thereby the type lever 64 is moved into striking position through the links 61, 62 and the bell crank 63, in which position the type strikes against the platen roller 1. During the striking movement of the type lever 64, a projection 65 thereon moves the universal bar 66 which extends transversely to the direction of the movement of all the type levers 64. The movement of the universal bar 66 is transmitted through a transmission member 67 jointed to the machine frame by means of an intermediate member 69, to a projection 68 on the transmission member 67, which projection actuates a pin 50 on the pawl body 11, in both case shift positions. Thereby the pawl body 11 which is mounted on the case shift frame 2 is pivoted about the axis 57 (Figs. 13 and 14). The movement of the universal bar 66 and the parts 61, 68, 69 connected thereto, also the rocking of the pawl body in clockwise direction in Fig. 15, take place against the action of springs, not shown in the drawings, which also effect the returning movement when the type lever 64 returns to the initial position under the action of the key lever restoring spring 51.

The case shift is effected by pressing the case shift key 70. Thereby the case shift key lever 73 is rocked about a pivot pin 75 whereby a projection 74 on said lever raises the case shift frame 2 along with the paper carriage 6 and platen 7.

In order to produce, besides the customary single length step, another of double length in one or both positions of the paper carriage, in the present case and according to the present invention, three different types of abutment members are provided, each of which is exchangeably connected with an individual key lever 25b, 25c or 25d, whereas no abutment members are connected to the group of key levers 25a nor to the dead keys 28e. The arrangement of these abutment members and their distribution over the individual key levers 25 may be made differently according to the desired key-board without fundamentally changing the principles of the machine. Changes can easily be made, even on the fully assembled machine, if a different arrangement of characters on the type levers and on the key-board is desired because, for this purpose, only the abutment members associated with the individual key levers 25 need be exchanged. According to the present invention, when typing, these abutment members influence the adjustable abutment 16 for the movable pawl 14 by means of transmission and intermediate members. The different possibilities of such influencing will be hereafter described individually.

On depressing the keys 28a which are associ-

ated with characters of normal width, the escapement mechanism of the paper carriage is actuated in the conventional manner so that the carriage 6 in the upper and lower case shift position is advanced with the normal step width. The key levers 25a have the conventional form as is obvious from Fig. 2 and are not provided with additional abutment members. The movable pawl 14 is freed on swinging the pawl body 11 and is moved by the action of spring 13 from the position indicated by solid lines in Fig. 13 into the position indicated by dashes and dots in the same figure in which position it is held by the abutment 16 which is under the influence of spring 41.

On operation of a key associated with a character of greater width, the movable pawl 14 is swung further from the position indicated by solid lines in Fig. 13 into the position shown in Fig. 14 so that a double step is accomplished.

In order to obtain a double width step in both positions of the paper carriage with certain selective keys 28b, abutment members are mounted on the ends 29 of the corresponding key levers 25b. In this case, these abutment member consist of screwed on or riveted on little plates 30b. On swinging the key levers 25b by operating the keys 28b, the plates 30b act in both case shift positions of the paper carriage on a transmission member, rail or rod 32 which extends across all key levers 25 and is far enough away from the rear ends 29 of the key levers 25 to remain untouched by the ends 29 when the key levers 25a, 25c and 25d, which have no such little plates, are operated. As more particularly obvious from Figs. 6 to 12, inclusive, the transmission member 32 is mounted on levers 34 which are fulcrumed at 33 to the machine frame 1. An arm 35 provided on one of the levers 34 is movably linked by a connecting rod 36 to one arm 22 of a setting device 20—21—22 which is preferably built as a bell crank lever. The setting device 20—21—22 is rotatably carried by a bolt 24 which is fixed to arm 23—shown in Figs. 13 and 14—of the case shift frame 2. Another leg 20 of the setting device 20—21—22 is linked to one end of the connecting member 19, the other end of which is rotatably connected to the two-arm lever 18 which is rotatably supported by the bolt 49. With its free end 17, lever 18 engages an extension or pin 48 of the abutment body 15 which carries the abutment 16 and is also fulcrumed to the bolt 49. Upon operation of the transmission member 32 by means of the little plates 30b of the key levers 25b, the elbow-lever 34—35 and with it the setting device 20—21—22 is moved counterclockwise (Figs. 6 and 7). With the aid of the intermediate members 19, 18, 48, the abutment body 15 and with it the abutment 16 is swung from the position shown in Fig. 13 into the position shown in Fig. 14, whereby the desired double width step of the paper carriage 6 is obtained. Since the transmission member 32 with the levers 34 is rotatably carried by the machine frame 1, only the position of the setting device 20—21—22 which is rotatably supported by the case shift frame 2 is changed with respect to the elbow-lever 34—35 when shifting the paper carriage 6 with the platen 7 from the lower case shift position (Fig. 6) to the upper case shift position (Fig. 10). Hereby the connection of lever arm 35 and setting device arm 22 is maintained by means of the connecting rod 36 which is movably linked to both parts. The arrangement of the setting device 20—21—22 is

such that it is not swung when changing over from the lower case shift position according to Fig. 6 to the upper case shift position as per Fig. 10. The transmission member 32 retains its position in front of the abutment plates 30b of key levers 25b in both case shift positions.

For such keys as are also freely selective and at the operation of which in the base or lower case shift position of the platen a single control step and in the upper case shift position of the platen a double step is required, the following arrangement is made.

When operating the keys 28c, the abutment body 15 carrying the abutment 16 is operated only when the paper carriage 6 with the platen 7 is in the upper case shift position. For this purpose, extensions 31 (Fig. 4) are provided at the ends 29 of the key levers 25c, and to these extensions are linked abutment members 30c which have the shape of short rods. With their free ends, these rods 30c engage the apertures 41 of a transmission member 40 which has preferably the shape of an angle iron extending across all the key levers 25. The number of apertures 41 in the angle iron 40 is equal to the number of keys 25, so that connection is prepared in advance for all keys. The member 40 is mounted on levers 38 pivotally mounted on the machine frame at 37 (Fig. 6). One of the levers 38 has a free arm 39 which carries an abutment pin 42. When typing in the lower case shift position of the paper carriage, the abutment pin 42 which, at the operation of key lever 25, is moved in a counterclockwise direction (Fig. 6) by means of the abutment member 30c and the transmission member 40, moves over the free arm 22 of the setting device 20—21—22 as is obvious from Fig. 8. The abutment 16 is not moved when operating in the lower case shift position, and a single step advance movement of the paper carriage is effected. When shifting the paper carriage into the upper case shift position (Fig. 10), the free arm 22 of setting device 20—21—22 is brought into the path of the abutment pin 42 so that, upon operation of a key 28c, the setting device 20—21—22 is moved counterclockwise by means of the pin 42 as is obvious from Fig. 11, and the abutment 16 for the movable pawl 14 is adjusted in the already described manner. The result of this is a double step when operating the key 28c and when the paper carriage is in the upper case shift position.

A fourth possibility of the coordination of the width of the steps of the paper carriage and the keys is that in the lower case shift position double steps and in the upper case shift position single steps are obtained. Upon depressing a key 28d (Fig. 5) the abutment body 15 carrying the abutment 16 is operated only when the paper carriage is in its lower case shift position. In order to accomplish this, the ends 29 of the key levers 25d are provided with extensions 31, and the latter with abutment members 30d. These members consist of rods, the free ends of which engage in the apertures 45 of a transmission member 44 which extends across all the levers 25d and for which an angle iron is preferably used. The number of apertures 45 in the member 44 corresponds to the total number of key levers 25. The member 44 is connected with levers 43 which are rotatably carried by bolts 37 attached to the machine frame 1. The lever 43 is provided with a projecting arm 46 extending below the cross-piece 21 of the setting device 20—21—22 (Figs. 6 and 13). When typing while the paper carriage is in the lower case shift position, the pro-

jecting arm 46, which is turned counterclockwise (Fig. 6) by the action of the key levers 25d and the cooperation of the abutment members 30d and the aperture 45, engages the cross piece 21 of the setting device 20—21—22, as is obvious from Fig. 9, and turns the setting device 20—21—22 also counterclockwise. Hereby the abutment body 15 is operated in the manner already described and with the cooperation of the intermediate parts 19, 18, 17, 48 and, with it, the abutment 16 for the movable pawl 14 so that in the lower case shift position and when depressing the keys 28d a double step of the paper carriage 6 is produced. In the upper case shift position, the cross piece 21 of the setting device 20—21—22 which is carried by the case shift frame 2 of the machine is removed from the acting range of the projecting arm 46, as is obvious from Fig. 11, so that, in this position, the setting device 20—21—22 and the abutment 16 are not influenced when operating the keys 28d, and a single step advance movement of the paper carriage 6 is produced.

The ends of the abutment members 30c and 30d extend so far into the apertures 41, 45 of the members 40, 44 that, when operating the members 40, 44 by one of the abutment members 30c, 30d, the ends of the other not operated abutment members 30c, 30d move longitudinally within the apertures 41, 45 and remain in engagement with the members 40, 44.

In order to assure an absolutely reliable and quickly acting adjustment of the movable pawl 14 at the various case shift operations and widths of steps of the paper carriage 6, the abutment body 15 carrying the adjustable abutment 16 for the pawl 14 according to this invention is rotatably carried by the main pawl body 11 by means of a bolt 49. In the single step position (Fig. 13), the abutment body 15 is held by means of spring 47 in a position which is determined by the abutment of a nose 52 provided on the body 15 against a pin 53 attached to the pawl body 11. The double lever 18 which is also operated by setting device 20—21—22 with the co-operation of connecting member 19 is also rotatably carried by the same bolt 49 attached to the pawl body 11.

When operating certain keys, the abutment body 15 is operated against the action of spring 47 by means of the double lever 18, the free end 17 of which engages the pin 48 of the abutment body 15 in such a way that the abutment 16 is always in the plane of the movement of the movable pawl 14. This arrangement assures that faulty adjustments are avoided which could easily happen if it were necessary that an especial abutment be moved into the path of the movable pawl 14 and across the direction of the movement of the latter. With the arrangement according to this invention, the abutment 16 reliably assumes the desired position at the correct moment, also when typing at highest speed.

In the position for double width steps, the movement of the abutment body 15 is limited by an abutment 54 provided on abutment body 15 which cooperates with the abutment part 55 associated with the pawl body 11. The movable pawl 14 is rotatably connected at 58 to the pawl body 11 and abuts, when in rest position according to Fig. 13, i. e., when the paper carriage stands still, with one arm 59 on which the spring 13 also acts against the abutment 60 of the pawl body 11. In this position the movable pawl 14 is held by means of the escapement wheel 10 which tries to turn the movable pawl 14 around

the fulcrum 58 and against the action of the spring 13 associated with pawl 14 in clockwise direction (Fig. 13) under the influence of the draw spring for pulling the paper carriage. The pawl body 11 is revolvably carried in known manner by the shaft 57 which is carried by the two arms 56 of the case shift frame 2.

While I believe the above described embodiments of my invention to be preferred embodiments, I wish it to be understood that I do not desire to be limited to the exact details of process, design and construction shown and described, for obvious modifications will occur to a person skilled in the art.

I claim:

1. In a typewriter having a machine frame, type carriers with different types thereon and means for case shifting the machine to print different types; paper carriage escapement mechanism comprising an escapement wheel, a rocking spacing device carrying escapement pawls cooperating with said wheel, one of said pawls being movable to control the spacing distance, an adjustable abutment determining the movement of said pawl into different positions corresponding to different spacing distances, a setting device for effecting adjustment of said abutment, said setting device being movable relatively to the machine frame during case shifting without changing the position of the abutment, key-actuated parts, and transmission means including actuator parts exchangeably mounted on selected key-actuated parts, said actuator parts being operative to actuate the setting device in such a manner as to change the position of said abutment and vary the spacing, and the transmission means also including a plurality of separately movable members each operated by actuator parts on different sets of key operated parts.

2. In a typewriter having a machine frame, type carriers with different types thereon and means for case shifting the machine to print different types; paper carriage escapement mechanism comprising an escapement wheel, a rocking spacing device carrying escapement pawls cooperating with said wheel, one of said pawls being movable to control the spacing distance, an adjustable abutment determining the movement of said pawl into different positions corresponding to different spacing distances, a setting device for effecting adjustment of said abutment and movably mounted on the case shifting frame, said setting device being movable relatively to the machine frame during case shifting without changing the position of the abutment, key-actuated parts, and transmission means including actuator parts exchangeably mounted on selected key-actuated parts, said actuator parts being operative to actuate the setting device in such a manner as to change the position of said abutment and vary the spacing.

3. In a typewriter having a machine frame, type carriers with different types thereon and means for case shifting the machine to print different types; paper carriage escapement mechanism comprising an escapement wheel, a rocking spacing device carrying escapement pawls cooperating with said wheel, one of said pawls being movable to control the spacing distance, an adjustable abutment connected to the setting device by a link and determining the movement of said pawl into different positions corresponding to different spacing distances, said rocking spacing device including a pivotable frame in which the movable escapement pawl and the adjustable

abutment means are pivoted, a setting device for effecting adjustment of said abutment, said setting device being movable relatively to the machine frame during case shifting without changing the position of the abutment, key-actuated parts, and transmission means including actuator parts exchangeably mounted on selected key-actuated parts, said actuator parts being operative to actuate the setting device in such a manner as to change the position of said abutment and vary the spacing.

4. In a typewriter having a machine frame, type carriers with different types thereon mounted in said frame and means including a case shift part for case shifting the machine to print different types, paper carriage escapement mechanism comprising an escapement wheel, a rocking spacing device carrying escapement pawls cooperating with said wheel, one of said pawls being movable to control the spacing distance, an adjustable abutment determining the movement of

said pawl into different positions corresponding to different spacing distances, a setting device for effecting adjustment of said abutment, said setting device being movable relatively to the machine frame during case shifting without changing the position of the abutment, key actuated parts, and transmission means including actuator parts exchangeably mounted on selected key-actuated parts and a plurality of separately movable transmission members each operated by actuator parts on different sets of key-operated parts, said actuator parts being operative to actuate the setting device in such a manner as to change the position of said abutment and vary the spacing, and said transmission members having projections cooperating with the setting device one of which projections acts on the setting device only in one case shift position while at least one other projection acts on the setting device only in a different case shift position.

WILLY EISELT.
